CLAIM

The ornamental design for a ferrule for optical fiber connectors as shown and described.

DESCRIPTION

1. Ferrule for optical fiber connectors

1.1 : Front

1.2 : Right

1.3 : Top

1.4 : Bottom

1.5 : Back

1.6 : Cross sectional

1.7 : Cross sectional

1.8 : Perspective

Name of this industrial design product: Ferrule for optical fiber connectors. Other necessary explanations or descriptions: Reproduction 1.6 is a side cross-sectional view along line A-A'. The Dash-Dash broken line represents the portions of the article that form no part of the claimed design and are directed to environment. The Dash-Dot broken line represents the claim boundary and forms no part of the claimed design.
